(57) **CLAIM**

The ornamental design for a reversible, waffled saddle pad, as shown and described.

DESCRIPTION

FIG. 1 is a perspective view of a reversible, waffled saddle pad of the present design, shown as if mounted on a horse (with the girth slit toward the front);

FIG. 2 is a top plan view of FIG. 1 but arrayed on a flat surface in which view the dotted line represents the stitching pattern;

FIG. 3 is a left side elevational view of FIG. 2, the right side elevational view being a mirror image thereof;

FIG. 4 is a front elevational view of FIG. 2, the rear elevational view being identical to the front elevational view;

FIG. 5 is a rear elevational view of FIG. 2; and,

FIG. 6 is a bottom plan view of FIG. 2.
